(57) **CLAIM**

The ornamental design for a waist support belt as shown and described.

DESCRIPTION

FIG. 1 is a front perspective view of a waist support belt showing my new design;

FIG. 2 is a front view thereof;

FIG. 3 is a rear view thereof;

FIG. 4 is a right side view thereof;

FIG. 5 is a left side view thereof;

FIG. 6 is a top view thereof;

FIG. 7 is a bottom view thereof;

FIG. 8 is a rear perspective view thereof; and

FIG. 9 is an enlarged view of detail “9”, identified in FIG. 8;

FIG. 10 is an enlarged view of detail “10”, identified in FIG. 6;

FIG. 11 is an enlarged view of detail “11”, identified in FIG. 6;

FIG. 12 is an enlarged view of detail “12”, identified in FIG. 7;

FIG. 13 is an enlarged view of detail “13”, identified in FIG. 7;

FIG. 14 is an enlarged view of FIG. 4; and,

FIG. 15 is an enlarged view of FIG. 5.
